UNITED STATES PATENT OFFICE

JAMES GLENNON, SR., OF ROCHESTER, MINNESOTA

DIRIGIBLE HEADLIGHT

Application filed May 13, 1929. Serial No. 362,694.

This invention relates to dirigible headlights for automobiles and it is designed more especially as an improvement upon the structures illustrated in my patents numbered 1,515,105 and 1,644,427.

It is an object of the invention to provide a means whereby the dirigible headlight can be adjusted for accurate connection with automobiles of different makes and sizes.

Another object is to provide a structure of this character that permits a limited movement of the front wheels from side to side without actuating the headlights, said structure operating, however, to turn the headlights to illuminate the path of the vehicle when the same is given a right or left turn.

Another object is to so arrange the mechanism constituting this invention that it can be carried by the chassis of the vehicle where it will not become clogged with mud, etc. splashed by the vehicle when travelling.

A further object is to improve generally upon the construction of a lost motion mechanism used in connection with the apparatus.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a front elevation of a portion of an automobile having the present improvements combined therewith, some of the parts being in section.

Figure 2 is a top plan view of the structure shown in Figure 1.

Figure 3 is a vertical transverse section through the lamp pedestals, their connections and adjacent parts.

Figure 4 is a section on line 4—4, Figure 3.

Figure 5 is a section on line 5—5, Figure 3.

Figure 6 is an enlarged section on line 6—6, Figure 3.

Figure 7 is a section on line 7—7, Figure 6. Figure 8 is a section on line 8—8, Figure 6. Figure 9 is a section on line 9—9, Figure 8. Figure 10 is a section on line 10—10, Figure 8.

Figure 11 is a section on line 11—11, Figure 8.

Figure 12 is a side elevation of that portion of the apparatus connected to the steering arm of an automobile.

Figure 13 is a section on line 13—13, Figure 12.

Figure 14 is an enlarged section on line 14—14, Figure 13.

Figure 15 is a view partly in elevation and partly in section of a portion of one of the lamp pedestals.

Referring to the figures, by characters of reference, 1 designates a portion of the chassis of an automobile supported by the front axle 2 having the usual steering knuckles 3 adapted to be operated, as ordinarily, by a rod 3' connected to a steering arm 4 which, in turn, receives its motion from the steering wheel in the usual way.

Mounted on the front portion of the chassis are tubular pedestals 5 each of which has an enlargement or head 6 at its upper end. Each of these heads or enlargements is provided with a circular race 7 in which are located balls 8. These balls support a disk 9 secured to a shaft 10 that is mounted for rotation within and extended downwardly through the pedestal 4. The upper end of the shaft is connected in any desired manner to a cap 11 which extends over and closes the head or enlargement 6 and has connected to it the base 12 of a lamp housing 13.

The two heads or enlargements 6 are connected by a transverse bar 14, preferably formed integral therewith, although it is to be understood that, if desired, this bar can be made of a separate piece suitably attached to the heads 6. The bar serves to support a rod 15 pivotally connected at its ends to the two disks 9 as shown particularly at 16 in Figure 4. A transversely arched cover plate 17 is mounted on and extends longitudinally of the bar 14 and serves to house strip or rod 15 which, as shown in Figure 4, is free to move

at its ends about the axis of rotation of the respective disks 9. Thus it will be seen that the two lamp housings 13 will be actuated simultaneously to turn to the right or to the left by reason of the connection 15—16 between the disks 9.

The lower ends of the pedestals 5 are secured in base rings 18 that are held to the chassis 1 by bolts 19 extending downwardly through the channeled sides of the chassis as shown particularly in Figures 6 and 7. The bolts at one side of the chassis have their lower end portions extended through a base plate 20 mounted on the bottom portion of the chassis and this base plate 20 is held properly spaced from the top of the chassis by sleeves 21 mounted on the bolts and fitted snugly at their ends in plate 20 and the top of chassis 1. The lower end of the adjacent shaft 10 is mounted in this plate so as to rotate relative thereto and formed in the upper face of the plate 20 directly back of shaft 10 is a recess 22. This recess is located midway between upstanding pins 23 and a pivot pin 24 extends upwardly from plate 20 directly in front of shaft 10.

Secured to the shaft 10 so as to rotate therewith is a segment 25 having an arcuate slot 26 concentric with shaft 10. A spring-pressed ball 27 is seated in the apex portion of the segment 25 where it is held under restraint by a screw plug 28. This ball is adapted to be seated in the recess or notch 22 when the segment is in its normal position as shown, for example, in Figures 6, 8, and 9.

Coiled springs 29 of equal strength are connected to the pins 23 and also to ears 30 extending in opposite directions from the segment. Each of these ears has an upstanding lug 31.

The pin 24 extending from plate 20 through the slot 26 constitutes the pivot of a latch 32 having oppositely extending wings 33 and an intermediate slot 34 extending into the latch from the outer edge thereof. Under normal conditions the free ends of the wings 33 are between and in contact with the lugs 31 as shown for example in Figures 6 and 10, these wings 33 being so shaped as to curve backwardly and engage the inner portions of the lugs 31.

An opening 35 is formed in the segment 25 and extending loosely into this opening 35 is the lower end of a pin 36 extending downwardly through the slot 34 from a forked arm 37 that is mounted on and adapted to swing relative to the shaft 10. This pin constitutes a means for pivotally connecting the arm 37 to the forward end of a rod 38.

Rod 38 is adapted to be so shaped as to extend rearwardly, downwardly, and laterally to pass under one side of the chassis 1 and thence rearwardly for attachment to the steering arm 4. As shown in Figure 2 rod 38 is preferably made up of two members screw-

threaded and connected by a turnbuckle 39. The rear end of the rod is downturned and mounted movably within a head 40 shown in Figures 12, 13, and 14. This head has a stem 41 reduced annularly as at 42, the said stem being mounted for rotation in a sleeve 43 provided with retaining screws 44 that extend into the space surrounding the reduced portion 42, thereby permitting rotation of the stem 41 but preventing its withdrawal from the sleeve 43.

The sleeve 43 is extended laterally from a plate 45 which, as shown in Figures 12 and 13, has slots 46 for the reception of bolts 47. These bolts are used for fastening the plate 45 adjustably to another plate 48 secured to the end of the steering shaft 49 to which the arm 4 is connected. Plate 48 has an arm 50 which laps the arm 4 and is held thereto by a clamp 51. Thus it will be seen that plate 45 and the parts connected thereto can be caused to move positively with the arm 4 when the steering wheel is actuated. As plate 45 is adjustably mounted, the throw of rod 38 can be regulated by bringing head 40 closer to or moving it farther from the axis of rotation of shaft 49.

By making the rod 38 of two parts adjustably connected, the distance between the head 40 and the pin 36 can be regulated to insure normal positioning of the lamp housings where they point straight ahead. With these adjustments the device can be installed readily on different makes and sizes of cars and the parts all adjusted to assume proper normal positions.

It is to be understood that plate 20 and the mechanism assembled therewith can all be properly housed so as to be fully protected from mud and the like. Consequently there is no danger of the mechanism becoming clogged and inoperative.

In practice it will be understood that, when the front wheels of the vehicle are turned to the right or to the left the arm 4 will swing back and forth. When the front wheels are turned but slightly as when travelling along a straight or curved road and passing traffic the movement of arm 4 due to the slight turning of the front wheels will cause a transmission of motion through the rod 38 to the pin 36 and this pin will be caused to work longitudinally of the short slot 35 and at the same time cause the latch 32 to swing slightly about its pivot 24.

As a result of the foregoing the shaft 10 to which the segment 25 is attached will not be rotated. When, however, the front wheels are given a decided turn to the right or to the left, as when it is desired to make a right hand or a left hand turn from a road, the pin 36 will be brought against one end of the slot 35 and will move sufficiently to swing the latch 32 so that one wing 33 will move inwardly out of engagement with the adjacent lug or ear 30 while the other wing 33 will move outwardly

out of engagement with the adjacent ear 30. Consequently continued movement of the pin will result in a thrust thereby against one end of slot 35 with the result that segment 25 will be moved away from normal position, elongating one of the springs 29 and moving the ball 27 out of the socket or recess 22. As segment 25 is attached to shaft 10, said shaft will be rotated and motion will be transmitted therefrom to the other shaft 10 through disk 9 and rod 15. The two lamp housings 13 will therefore be swung in the direction in which the vehicle is turning.

As soon as the steering mechanism is shifted to straighten out the vehicle after making a turn, pin 36 will first thrust against one wall of slot 34 so as to cause the latch 32 to swing about its pivot 24 and assume a position between lugs 31 as indicated for example in Figures 6 and 10. This action will result in the wings 33 wiping against lugs 31 and swinging the segment 25 so as to impart a quick return movement of the shaft 10, this movement being supplemented by pressure of the pin 36 against the end of opening 35 which will bring the segment ultimately to its normal position with ball 27 seated in recess 22. It might be stated that the spring 29 that has been under tension will act to automatically return the segment to its initial position as soon as the pin 36 starts back.

In Figure 15 there has been shown an oil hole 52 in the cap 11 on head 6 of the pedestal. This can be normally closed by a screw plug 53 which, when removed, will allow the ball bearing to be lubricated readily.

What is claimed is:

1. A dirigible headlight structure for automobiles including connected shafts mounted for simultaneous rotation, a segment rotatable with one of the shafts, a base constituting a support for the segment, ball and socket means carried by the base and segment for holding said segment against free movement away from normal position, springs connecting the segment and the base for holding said segment normally in said position, a steering arm, and a lost motion connection between said steering arm and the segment, said connection including an arm mounted to swing, means for transmitting motion to the arm from the steering arm, a pivoted latch having oppositely extended wings, means on the segment for engagement by the wings, and means movable with the swinging arm for swinging the latch relative to the segment and subsequently shifting the segment.

2. A dirigible headlight mechanism for automobiles including lamp housings, shafts connected thereto and mounted for rotation, a chassis having a channeled side, a base plate mounted therein, fastening bolts extending through said side and the base plate, means on the bolts and bearing against the plate for holding it against displacement rel-

ative to the chassis, a segment mounted for rotation with the shaft and upon the base plate, said segment having an arcuate slot, a pivot pin mounted on the base plate and extending through the slot, yielding means for holding the segment normally in a predetermined position, cooperating means on the segment and base plate for holding said segment against free movement, a latch pivotally mounted on said pin and supported by the segment, said latch having oppositely extending superposed wings, upstanding lugs on the segment normally engaging the ends of the wings, an arm mounted for free rotation, a pin extending from the arm and through the latch and loosely mounted in the segment thereby to provide a lost motion connection between the arm and the segment, an automobile steering arm, and an operating connection between said arm and the pin-carrying arm.

3. A dirigible headlight structure for automobiles including lamp housings, connected shafts for rotating the same, a steering arm, a plate detachably connected to and movable with the steering arm, a second plate adjustably connected to said first named plate, a rod pivotally connected to and shiftable by the adjustable plate, said rod being adjustable to increase or reduce its length, and a lost motion connection between the rod and one of the shafts.

4. The combination with steering mechanism of a rotatable shaft for supporting a headlight, a member rotatable with the shaft, resilient means for holding the member normally in a determined position, and a lost motion connection between the steering mechanism and said member, said connection including an element adapted to be shifted relative to the rotatable member by the action of the steering mechanism, a latch having oppositely extended wings and pivotally mounted between its wings, means carried by the member on the shaft for engagement by the respective wings, and means movable with the element actuated by the steering mechanism for swinging the latch relative to the member on the shaft and subsequently shifting said member.

In testimony that I claim the foregoing as my own, I have hereto affixed my signature.

JAMES GLENNON, Sr.
